CLAIM

The ornamental design for a package with an icon, as shown and described.

DESCRIPTION

FIG. 1 is a perspective view of a package with an icon embodying our new design;

FIG. 2 is a front view thereof;

FIG. 3 is a left side view thereof;

FIG. 4 is a rear view thereof;

FIG. 5 is a right side view thereof;

FIG. 6 is a top view thereof; and,

FIG. 7 is bottom view thereof.

The broken lines are shown for the purpose of illustrating parts of the article that form no part of the claimed design.

The claim is limited to the details shown in solid lines in FIGS. 1 and 2.

1 Claim, 4 Drawing Sheets
